United States Patent Office

Des. 225,014
Patented Oct. 31, 1972

225,014

STOCK QUOTATION TERMINAL

Harold M. Weinberg, Villanova, Pa., assignor to
Sonex, Inc., Philadelphia, Pa.

Filed Jan. 29, 1971, Ser. No. 111,164

Term of patent 14 years

Int. Cl. D14—02

U.S. Cl. D26—5

FIG. 1

FIG. 2

FIG. 3

FIG. 4

FIG. 6

FIG. 5

FIG. 1 is a perspective view of a stock quotation terminal showing my new design;

FIG. 2 is a top plan view thereof;

FIG. 3 is a side elevational view thereof;

FIG. 4 is a side elevational view taken from the other side thereof;

FIG. 5 is a front elevational view thereof; and

FIG. 6 is a rear elevational view thereof.

I claim:

The ornamental design for a stock quotation terminal, substantially as shown.
